UNITED STATES PATENT OFFICE.

VAN N. MARKER, OF CHICAGO, ILLINOIS.

COMPENSATING STARTING SWITCH.

1,422,592.

Specification of Letters Patent. Patented July 11, 1922.

Application filed October 23, 1919. Serial No. 332,659.

To all whom it may concern:

Be it known that I, VAN N. MARKER, a citizen of the United States, and a resident of Chicago, in the county of Cook and State 5 of Illinois, have invented certain new and useful Improvements in Compensating Starting Switches; and I do hereby declare that the following is a full, clear, and exact description thereof, reference being had to 10 the accompanying drawings, and to the characters of reference marked thereon, which form a part of this specification.

This invention relates to an improved switch mechanism for controlling electric 15 circuits and refers more particularly to switches for use in connection with alternating current motors or other translating devices for applying different current voltages from the line when starting and when 20 running the motor.

The invention is herein shown as, embodied in a two-throw switch mechanism having a plurality of blades which operate in connection with one set of contacts or 25 clips and compensating coils in its starting position to reduce the line voltage on a motor or other translating devices when starting the same, and to be shifted to its running position, after the motor or other translating device has been energized for operation, to throw the full line voltage on the 30 motor or other translating device.

In switch mechanism of this general character as heretofore constructed it has been 35 proposed to interpose between the source of current supply and the motor compensating coils so connected to the current source and to the motor or other translating device as to reduce or absorb a portion of the electro- 40 motive force of the line when the switch is in position for starting the motor, so as to thereby avoid overloading the motor when starting. The said coils are so connected to the motor circuit and to the switch mech- 45 anism that controls it as to be cut out of the motor circuit when the switch is thrown to its running position to deliver the full line voltage line to the motor.

Among the objects of the present invention is to provide a switch mechanism of 50 this general character for connection to the operating circuit and motor so arranged that the compensating coils which act in the starting position of the switch to cut down the line voltage are completely disconnected

from the motor line circuit when the switch is in running position so as to thereby avoid leakage of current therefrom during the operation of the motor and to also enable the compensating coils to be safely and conveniently removed from the switch mechanism and others substituted therefore while the 60 motor is running.

Another object of the invention is to simplify the switch mechanism as to its contacts and bus bar connections and to make it of fewer, relatively more compact and simple parts than prior switch mechanisms. 65

Other objects of the invention are to otherwise improve switch mechanisms of the 70 general class described, and the invention consists in the combination and arrangement of the parts shown in the drawings and described in the specification, and is pointed out in the appended claims. 75

In the drawings,—

Figure 1 is a plan view of the mechanical parts of the switch mechanism embracing the invention.

Figure 2 is a side elevation thereof. 80

Figure 3 is a partial rear elevation, showing the bus bar connections.

Figure 4 is a diagrammatic view illustrating the wiring connections associated with the switch mechanism, the compensating 85 coils, the translating device, and the line circuit.

In said drawings, 10 designates an insulating base on which the switch mechanism is mounted. 11, 12, 13 designate the terminals 90 to which are, respectively, connected the line wires 14, 15, and 16 of a three-wire feed line. Said terminals are connected to clips 17, 18, and 19 supported on the base which are adapted, by means of a removable switch 20, 95 to be connected to opposing clips 21, 22, 23 supported on said base, the latter clips being connected by fuse elements 24, 25, 26, to running clips 27, 28, and 29.

30 designates, as a whole, a two-throw 100 switch which comprises main blades 31, 32, 33 connected by the usual insulating cross bar 34. Said blades 31, 32, 33 are adapted, in the running position of the switch, to connect said terminals 27, 28, 29 to the wires 35, 36, 105 37 of the motor circuit through terminals 38, 39, 40, mounted on the base to which said blades are hinged in a known manner. 41, 42, 43 designate clips in line with clips 27, 28, 29, respectively, which are adapted to be 110

engaged by the switch blades 31, 32, 33, when the switch is in its starting position. 44 designates a supplemental clip in line with, but spaced from the intermediate clip 42 in the 5 plane of the switch blade 32, said blade 32 being adapted to bridge over the clips 44 and 42 when the switch is in its starting position. The said supplemental clip 44 is connected, in the rear of the base 10, by a bus bar 45 to 10 the clip 28 as shown in Figure 3.

The clips 41 and 43 are, respectively, adapted to be connected by terminals 46, 47 and wires 48, 49 to intermediate points along the length of adjustable compensating coils 15 50, 51, respectively, and the intermediate clip 42 is connected, through a terminal 52 and a wire 53, with a common connecting wire 54 between corresponding ends of said coils 50 and 51.

20 The switch is provided, in addition to the blades 31, 32, and 33, referred to, with other blades 55, 56 that are hinged to the respective terminals 57, 58 on the base which, latter terminals are connected by oblique bus bars 25 59, 60, to the respective clips 27 and 29. 61, 62 designate clips which are connected to the ends of the compensating coils 50, 51, respectively, remote from the ends thereof that are connected by the cross connection 54 before 30 referred to, and said clips 61, 62 are adapted for contact by the outer blades 55, 56 of the switch when the latter is in its starting position.

When the two-throw switch is in its starting 35 position the intermediate blade 32 thereof bridges across the clips 44, 42, the said blade connecting said spaced terminals 42, 44 with the hinge terminal 39. The next adjacent blades 31, 33 of the two-throw switch 40 connect the hinge terminals 38, 40, in the starting position thereof, with the clips 41, 43, and the outer blades 55, 56 connect the hinge terminals 57, 58 with the clips 61, 62 in the starting position of the switch. The 45 line circuit is thus closed to the motor M through the coils 50, 51 so that the voltage of the line is reduced to an extent depending on the connection of the wires 48, 49 with the coils. In the starting position of the 50 switch it will be noted that the corresponding ends of the coils 50, 51, adjacent the switch, are connected to the terminals 27, 29 through the bus bars 59, 60 and the outer switch blades 55, 56.

55 When the switch is thrown over to the running position the switch blades 31, 32, 33, respectively, connect the hinge terminals 38, 39, and 40 to the clips 27, 28, and 29, so that the feed line is connected directly to the 60 motor, with the full voltage of the feed line on the motor.

As has hereinbefore been pointed out the B phase of the line is connected to the coils 50, 51 when the switch is in its starting position through the blade 32 bridging across

the clips 44, 42, and from what has been said, it will be furthermore noted that when the switch is thrown to its running position, the B phase line to the coil is broken between the clips 44, 42. It will be furthermore observed 70 that when the switch is thrown from its starting position to its running position the coils 50, 51 are not only disconnected between the clips 44, 42, but that the circuit through said coils is also open at the ends and centers 75 of the coils 50, 51 by movement of the blades 55, 56, 31, 33 away from the clips 61, 62, 41, 43, and that the blades 55, 56 in the running position of the switch, become dead or inactive blades. From what has been said, it 80 will be observed that when the switch is thrown from its starting to its running position, no voltage is impressed on the coils 50, 51, so that there is no possibility of leakage of current through the coils in event said 85 coils should become grounded. It will be furthermore noted that, by reason of the spaced terminals 44, 42 that connect the B phase of the line with the outer ends of the coils, the said coils and their mountings may 90 be separated from the switch mounting and the coils repaired or replaced without in any manner disturbing the connection of the line to the motor and while the motor is running.

95 Preferably and as herein shown the switch is closed upon its starting contacts 61, 41, 42, 43, and 62 against a resilient or spring action tending to separate the switch blades from said terminals when closing pressure on the switch is released, and is likewise 100 closed on its running contacts 27, 28, 29 against a yielding or spring pressure. The switch is adapted to be locked in its running position by an automatic no-volt release device.

105 The spring means against which the switch is closed in its starting position embraces a cross bar 65 which is mounted transversely over the front face of the base 10 to slide on outstanding stems 66 which are clamped on 110 the base, and the bar is normally held away from the base by spiral expansion springs 67 interposed between the bars and the base, the bars being adapted to slide rearwardly on the stems. Said bar 65 is of a length 115 to be engaged by the three intermediate switch blades, 31, 32, 33. During the starting position the switch is held closed by hand until the motor attains the desired speed, whereupon the switch is manually quickly 120 thrown to its running position.

125 The spring means against which the switch is closed to its running position is like the spring means before described, embracing a cross bar 69, fixed stems 70, and springs 71 that normally hold the bars outwardly from the base. The switch is locked in its running position, against the compression action of said springs 71 by a locking device comprising a swinging hooked latch 73 that 130

is pivoted at 74 to a bracket on the rear side of the base and extends through an opening 75 in the base, the hook 76 of the lever being adapted to engage over the cross bar 34 of the switch. The said latch is so weighted, with respect to its pivot 74, that it normally tends to assume the position shown in Figure 2 when no current is on the feed line, and is adapted to be swung with its hooked 10 end for engagement with the cross bar of the switch when current is traversing the feed line by a magnet 77 which is connected between the A and B phase of the line, as best shown in Figure 4. Therefore, said magnet 15 normally holds the latch in its locking position with its hook 76 engaged over the bar 34 when the switch is in its running position. Upon failure of current on the line, the magnet is de-energized and the overbalancing effect of the locking latch, assisted, 20 if necessary, by a light spring, withdraws the hook end of the latch from the switch bar 34 so that the said switch is free to be thrown open by the springs 71.

It will be understood that so far as certain features of the invention is concerned, the details shown are capable of some variation within the spirit and scope of the claims hereto appended, and that the invention is 30 not limited to said details except as they are embraced in specific claims, and as limited by the prior art, it being the intent to claim all of inherent novelty in the disclosure.

The contacts with which the switch blades 35 and the cut-out switch contact are herein termed clips because assuming a split or clip form of contact. However, the contacts may be otherwise made.

I claim as my invention,—

40 1. In combination with a source of electrical energy, a translating device and compensating coils, of a multiple blade, double throw switch hinged to the translating device terminals for connecting said translating device to the line in the running position thereof, said coils having a common terminal, pairs of terminals of branch coil circuits with which, and the common terminal, the switch blades are connected in the starting position of the switch, and means whereby said common terminal is completely disconnected from the line in the running position of the switch.

2. The combination with a three wire 55 feed line, a motor and compensating coils connected to a common terminal, of a multiple blade, double throw switch hinged to the motor circuit terminals for directly connecting said motor circuit to the line in the running position of the motor, and having auxiliary blades cooperating with the main blades for connecting said motor circuit terminals in divided circuits with said coils and to said common terminal in the starting position of the switch and arranged to com-

pletely disconnect said coils from all the wires of said line when the switch is in its running position.

3. The combination with a three-wire feed line, a translating device and compensating coils, of switch mechanism embracing three members and their contacts for directly connecting the translating device to the line in the running position of the switch, and embracing additionally two members adapted in the starting position of the switch, together with said three members, to close on contacts connected to said coils, whereby the line energy is transmitted to the translating device through said coils, said coil contacts 75 and the switch members being constructed to disconnect the coils from all the wires of the line when the switch is in its running position.

4. The combination with a three-wire feed line, a translating device and compensating coils, of a switch mechanism embracing three members and their contacts for directly connecting the translating device to the line in the running position of the switch, and embracing two additional members, said coils having terminals for contact with all the switch members in the starting position of the switch, one of said latter terminals 90 common to both coils, and the other terminals being connected in series with the coils, and means whereby the contact common to said coils is disconnected from the line when the switch is thrown from its starting position to its running position. 100

5. The combination with a three-wire feed line, a translating device and compensating coils, of a switch mechanism embracing three members and their contacts for directly connecting the translating device to the line in the running position of the switch, and embracing two additional members, said coils having terminals for contact with all the switch members in the starting position of the switch, one of said latter terminals 105 common to both coils, and the other terminals being connected in pairs in series with the coils, and a supplemental terminal electrically disconnected to the terminal common to said coils and in line with said latter terminal across which one member of the switch is bridged when in the starting position. 110

6. The combination with a three-wire feed line, a translating device and compensating coils, of a switch mechanism adapted in its running position to directly connect the feed line to the translating device, and when in its starting position to connect the feed line to the translating device through said coils, said switch embracing pairs of members which, when the switch is in its starting position are connected from two of the line wires in series through the coils to the translating device, and another member which is adapted to close on a termi- 125 130

nal connected between the coils, and means whereby said coils are disconnected from all the wires of the feed line when the switch is in its running position.

- 5 7. The combination with a three-wire feed line, a translating device and compensating coils, of a switch mechanism adapted in its running position to directly connect the feed line to the translating device, and when in 10 its starting position to connect the feed line to the translating device through said coils, said switch embracing pairs of members which, when the switch is in its starting position, are connected from two of the line wires 15 in series through the coils to the translating device, a terminal connected between said coils, and a supplemental terminal in line with the latter terminal and disconnected from the coils and connected to the third line 20 wire, said switch embracing a single member adapted, in the starting position of the switch to bridge between said latter terminals and thereby connect the third line wire between said coils.
- 25 8. The combination with a three-wire feed line, a translating device and compensating coils, of a switch mechanism adapted in its running position to directly connect the feed line to the translating device and in its 30 starting position to connect the feed line to the translating device through said coils, said switch embracing two pairs of members which, when the switch is in its starting 35 position, connect two of the line wires through said coils to the translating device and a fifth member which, when the switch is in its starting position, is adapted to bridge between two disconnected contacts or 40 terminals that are connected, respectively, between said coils and to the third wire of the feed line.

9. The combination with a three-wire feed line, a translating device and compensating coils having a common terminal connected

between said coils and other terminals connected in pairs in series to the respective coils, of a switch embracing three main blades hinged on terminals connected to the translating device and adapted in the running position thereof for connection with the three wires of the line, and comprising also two supplemental blades connected to two wires of the line, all of said blades, in the starting position of the switch being adapted for contact with the coil terminals, and means whereby said common terminal is disconnected from the line when the switch is thrown from its starting position to disconnect the other coil terminals from the line.

10. The combination with a three-wire feed line, a translating device and two compensating coils having a common terminal and other terminals connected in pairs in series to the coils, of a swinging switch 65 embracing a central blade and two side blades adapted in the starting position of the switch for respective contact with said common coil terminals and with one of the series connected contacts of each coil, and 70 hinges for said blades electrically connected to the translating device, said switch comprising also other blades hinged in line with said first mentioned blade hinges and electrically connected with two of the line wires 75 and adapted in the starting position of the switch for contact with other terminals of the coils, the common coil terminal being disconnected from the line when the switch is thrown from the starting position.

In testimony, that I claim the foregoing as my invention I affix my signature in the presence of two witnesses, this 13th day of October, A. D. 1919.

VAN N. MARKER.
